UNITED STATES PATENT OFFICE.

ANTON UHER, OF ORD, NEBRASKA.

GRAIN-ADJUSTING DEVICE.

Application filed November 20, 1926. Serial No. 149,657.

This invention relates to certain new and useful improvements in grain adjusting devices for grain harvesters, and has more particular reference to improved butt and head 5 evening devices for use upon the inclined binder deck of a grain harvester.

The primary object of the invention is to provide improved grain adjusting devices of the above kind by means of which the grain 10 may be evened in an effective manner for being formed and tied into bundles of the desired proper shape.

A more specific object of the invention is to provide grain adjusting devices of the 15 above kind embodying a head evening device which is extremely simple and durable in construction as well as efficient in operation.

A still further object is to provide an improved head evener which will not readily become out of order, which may be readily adjusted to even grain of varying lengths, and which requires no gearing or similar driving mechanism to cause movement or oscillation of the same for its function.

With the above general objects in view, and others that will become apparent as the nature of the invention is better understood, the same consists in the novel form, combination and arrangement of parts hereinafter 30 more fully described, shown in the accompanying drawings and claimed.

In the accompanying drawings, wherein like reference characters indicate corresponding parts throughout the several views, Figure 1 is a fragmentary plan view of a binder deck and adjacent parts of a grain harvester provided with an improved head evener constructed in accordance with the 40 present invention;

Figure 2 is a rear elevational view of the device shown in Figure 1;

Figure 3 is a cross sectional view of the binder table and adjacent parts provided 45 with a butt evener constructed in accordance with the present invention; and

Figure 4 is a top plan view of the device shown in Figure 3 revealing the relation of the head evener of Figures 1 and 2 and the 50 butt evener of Figure 3 upon the binder deck.

Referring more in detail to the drawings, 5 indicates the main frame of the harvester, which is supported at one side by a master 55 or drive wheel 6. The inclined binder deck is indicated at 7, and the grain is delivered

onto this deck from the cutting mechanism of the harvester (not shown) by the inclined elevator aprons 8, to be formed and tied into bundles in a generally well known manner. 60

Disposed edgewise upon the front end portion of the binder deck 7 so as to extend rearwardly and outwardly from the adjacent end of the forward side wall 9 of the conveyor frame for the aprons 8, is an arcuate sheet metal plate 10 constituting the butt evener board. The plate 10 is formed upon its inner end with projecting spaced curved tongues 11 loosely fitting in slots provided as at 12 in the adjacent outer end of the 70 conveyor wall 9, whereby the plate or head evener board 10 is mounted upon the deck 7 for swinging movement in an inclined plane parallel with the plane of the binder deck 7. Rigid with and projecting forwardly 75 from the outer free end portion of the plate or board 10 is an adjusting screw 13 which slidably projects through the outer end of the wall 9 as shown clearly in Figure 4, and threaded upon the screw 13 at opposite sides 80 of the upstanding arm of wall 9 are jamb nuts 15. By reason of this construction it will be apparent that upon backing one of the nuts 15 away from the wall 9 and tightening up upon the other nut, the butt evener plate or board 10 may be swung and thereby 85 adjusted rearwardly or forwardly to the desired position, the same being retained in its adjusted position by tightening the nuts 15 against opposite sides of the wall 9. 90

Disposed edgewise upon the rear edge portion of the binder deck 7 is a head evener board composed of a pair of sections 16 and 17 hingedly connected at adjacent ends as at 18 upon an axis parallel with the plane of the board sections and at right angles to their longitudinal axes. The inner end of the inner board section 16 is hinged as at 19 to the adjacent end of the rear side frame board 20 of the conveyor aprons 8, whereby the head evener board is mounted to swing bodily upon the binder deck 7 parallel with the inclined plane of the latter. A link connection is provided at the outer side of the head evener board and between the intermediate portion of the outer section 17 of the latter and a fixed part adjacent the inner pivoted end of the inner board section 16. As shown, this link connection preferably consists of a rod 21 having an upwardly directed outer end 22 journaled in a bearing bracket 23 fixed to the rear or outer side 100 105 110

of the board section 17 intermediate the ends of the latter, said rod 21 further having a downwardly directed inner end journaled in a bearing bracket 24 constituting said fixed part and rigidly attached to the frame of the conveyor formed in part by the aprons 8. A helical tension spring 25 or other elastic tension device is attached at one end as at 26 to the inner side of the forward conveyor frame wall 20 inwardly of the pivot 19 of the head evener board, and this spring extends outwardly through a relatively large opening 27 provided in the inner board section 16 and has its outer end attached to the intermediate portion of the link 21. The means for attaching the spring 25 to the link 21 preferably embodies a slide 28 adjustable longitudinally on the link 21 and having an upstanding hook 29 engageable in an eye provided on the end of the spring 25.

As the grain is delivered onto the binder deck 7 from the aprons 8, it will pass outwardly between the head and butt evener boards shown in Figure 4, the butts being evened by the board 10 by riding outwardly against the forwardly and outwardly curved forward surface of the same. At the same time, the heads of the grain will be evened by the head evening device, the board sections of which will be normally maintained at the more acute angle relation as shown by dotted lines in Figure 4 by reason of the spring 25 pulling inwardly upon the link 21 and causing the latter as well as the inner board section to swing inwardly about their inner hinge connections 19 and 26. As the heads of the passing grain press against the outer end of the diagonally disposed inner board section 16, it will force the latter forwardly against the action of the spring 25, and in so doing, the link 21 will be forced to swing rearwardly while the outer board section 17 will swing about its pivotal connection with the outer end of link 21 so as to assume a position parallel with the direction of movement of the grain as shown by full lines in Figure 4. While this is taking place, the outer board section 17 is held yieldingly into engagement with the heads of the grain by the spring 25 so that a pressure is exerted upon the heads for evening the same, the board sections 16 and 17 undergoing a slight vibrating action during the evening operation.

The tension of the spring 25 may be adjusted to suit the requirements of different kinds of grain by adjusting the slide 28 longitudinally on the link 21, said slide being of clamp formation for this purpose. Thus, an efficient operation of the head evener is insured under various conditions.

It is noted that the adjustment of the slide 28 and the consequent adjustment of the tension of spring 25 may also act as a fine ad-

justment for proper action upon grain of different lengths, the rough adjustment being obtained by the adjustment of the butt evener board 10.

From the foregoing description it is believed that the construction and operation as well as the advantages of the present invention will be readily understood and appreciated by those skilled in the art.

Minor changes may be made without departing from the spirit and scope of the invention as claimed.

What I claim as new is:—

1. The combination with a binder deck and a fixed part above and at the front inner part of said deck, said fixed part being provided with slots, a butt evener board provided upon its receiving end with projecting tongues pivotally engaged in said slots so that said board is mounted for swinging movement upon the deck, and means associated with the fixed part and the free outer end of said board for permitting swinging adjustment of the latter and securing it in adjustably swung positions.

2. The combination with a binder deck and a fixed part above and at the front inner part of said deck, said fixed part being provided with slots, a butt evener board provided upon its receiving end with projecting tongues pivotally engaged in said slots so that said board is mounted for swinging movement upon the deck, and means associated with the fixed part and the free outer end of said board for permitting swinging adjustment of the latter and securing it in adjustably swung positions, said last named means embodying an adjusting screw rigid with and projecting rearwardly from the free end of said board and extending through said fixed part, and jamb nuts threaded upon the adjusting screw at opposite sides of the fixed part.

3. In combination with a binder deck, a head evener board hinged at its inner end upon said deck and comprising a pair of hingedly connected board sections, a fixed part forwardly of and near the inner end of said board, a link connection between said fixed part and the outer side of the intermediate portion of the outer section of said board, and an elastic tension element connected to the link between its ends and extending inwardly freely through the inner board section and attached to a fixed part rearwardly and inwardly of the inner end of the inner board section.

4. In combination with a binder deck, a head evener board hinged at its inner end upon said deck and comprising a pair of hingedly connected board sections, a fixed part forwardly of and near the inner end of said board, a link connection between said fixed part and the outer side of the intermediate portion of the outer section of said

- board, and an elastic tension element connected to the link between its ends and extending inwardly freely through the inner board section and attached to a fixed part 5 forwardly and inwardly of the inner end of the inner board section, and a slide adjustable longitudinally of the link and having the outer end of the elastic tension element attached thereto.
- 16 5. A head evening device for grain harvesters comprising an evener board, means to pivotally attach the inner end of said board to the harvester whereby the board is

mounted for swinging movement upon the harvester deck, and yieldable means for 15 swinging the board in a forward direction on the deck, said board comprising a pair of hingedly connected sections, and a link disposed forwardly of the board having its outer end pivotally attached to the rear side 20 of the intermediate portion of the outer section of the board and having its inner end pivotally attached to a fixed part of the harvester.

In testimony whereof I affix my signature.
ANTON UHER.
